UNITED STATES PATENT OFFICE.

EDMUND LUNKENHEIMER, OF CINCINNATI, OHIO.

OIL-CUP.

SPECIFICATION forming part of Letters Patent No. 317,464, dated May 5, 1885.

Application filed February 28, 1885. (No model.)

To all whom it may concern:

Be it known that I, EDMUND LUNKENHEIMER, of Cincinnati, in the county of Hamilton and State of Ohio, have invented certain new and useful Improvements in Oil-Cups, of which the following is a specification.

My invention is in the nature of an improvement upon an oil-cup for which Letters Patent of the United States were granted me June 3, 1884; and it consists in the adaptation to such cups of certain novel devices whereby the cup may be recharged with oil or other lubricant without removing the cover or changing the feed, all of which will be fully shown hereinafter.

In the accompanying drawings, Figure 1 is a sectional elevation of my improved oil-cup, and Fig. 2 a plan thereof. Fig. 3 is a plan of the oil-cup shown in Fig. 1, with the feed-screw and binding-nut removed; and Fig. 4, a plan of the washer used in connection with my present arrangement of the refilling device.

Similar letters of reference indicate similar parts.

The general construction of the oil-cup is similar to that described in my former patent, and consists of the base A, cylindrical glass shell B, stem C, to regulate the feed of the oil, cover or cap D, hollow stem a², and elastic washers b b', to prevent injury to the glass shell.

The operation of the cup, so far as it relates to the method of feeding the oil from it, is precisely like my former cup, the oil flowing from the body of the cup through the orifice a⁴, past the screw-point c of regulating stem C, through the orifice a³ of the base of cup, to the parts to be lubricated.

The position of the feed-stem C determines the rate at which the oil is fed from the cup.

D' is a lever or arm fitted to the upper end of the hollow stem a², and pressed upon by the binding-nut E through the D-washer e, one side of the hollow stem a² being flattened, as at e², to receive the washer. The lever or arm D' turns upon the hollow stem a² with more or less friction, according to the pressure imposed upon the washer e by the binding-nut E; but while the arm D' may be oscillated upon the stem a², the washer e is prevented from turning by the flat e' upon one side, as

shown in Fig. 4, which fits a corresponding flat on stem a², as shown in Fig. 3.

d² d² are stop-pins secured to the cover D, which limit the oscillating motion of the arm D'. The pressure of the nut E upon the arm D' being applied through the washer e prevents the motion of the arm from being imparted to the nut, and the motion of the arm cannot therefore either tighten or loosen the nut upon the stem a². The binding-nut E not only regulates the friction against which the arm D' must be moved, but also holds the glass shell B, cover D, and elastic washers b b' in position in the cup.

d' is an orifice in the cover D of the cup, through which the lubricant is introduced, the arm D' moving from right to left, and vice versa, to open and close said orifice d', as may be necessary to refill the cup with oil.

Referring to Fig. 2, the arm or lever D' is moved in the direction to uncover the filling-orifice d', while in Fig. 3 the arm is shown in the opposite position and the orifice d' covered.

The frictional resistance due the pressure of the binding-nut E between the cover D and the washer e upon the upper and lower surfaces of the hub of the arm D' is sufficient to prevent displacement of the arm D' in the proper use of the cup.

Having described my invention, what I claim is—

The combination, with an oil-cup having a cover, D, provided with an orifice, d', of the tubular stem a², projecting through the cover and provided with a flattened side, e², the arm D', journaled at one end on the stem, the washer e, bearing on the upper side of the arm, and the flattened portion e', fitting the flattened side of the stem, and the screw-nut E, bearing on the washer, whereby the swinging movements of the arm to cover and uncover the orifice d' are prevented from being transmitted to the nut, substantially as described.

In testimony whereof I have signed my name to the foregoing specification in the presence of two subscribing witnesses.

EDMUND LUNKENHEIMER.
